UNITED STATES PATENT OFFICE.

JAMES BATES, OF LORAIN, OHIO.

JAR CABINET.

Application filed March 10, 1923. Serial No. 624,188.

To all whom it may concern:

Be it known that I, JAMES BATES, a citizen of the United States, residing at Lorain, in the county of Lorain and State of Ohio, ⁵ have invented certain new and useful Improvements in Jar Cabinets, of which the following is a specification.

My invention relates to cabinets which are primarily but not specifically adapted ¹⁰ for the reception of fruit, nut and syrup jars employed in conjunction with soda fountains, the nature of my cabinet being such as to receive a large number of these jars and for permitting the ready access to ¹⁵ the same, the cabinet being well adapted to be positioned at a convenient place upon the soda fountain.

A further object of the invention resides in the provision of such a cabinet that is of ²⁰ simple construction, comparatively inexpensive of manufacture and highly useful for the purpose intended.

The nature and advantages of the invention will be better understood when the following detailed description is read in connection with the accompanying drawings, the invention residing in the construction, combination and arrangement of parts as ²⁵ claimed.

In the drawings forming part of this application, like numerals of reference indicate similar parts in the several views, and wherein:—

Figure 1 is a top plan view of a cabinet constructed in accordance with my invention, one of the top walls of the same being partly broken away.

Figure 2 is a front elevational view thereof.

Figure 3 is a vertical transverse cross sectional view upon the line 3—3 of Figure 1, and

Figure 4 is a perspective of a desirable form of fruit or nut jar to be used in conjunction with my cabinet.

The jar cabinet is generally indicated at 1, and includes a rear wall 2, a bottom wall 3, and a connecting wall generally indicated at 4, which extends from forward edge of the ⁵⁰ bottom wall as indicated at 5, to the upper edge of the rear wall as indicated at 6. This connecting wall portion is formed with step portions, the steps of which are generally indicated at 7, and which include horizontal offset portions 8, which are formed ⁵⁵ with a plurality of openings 9, and are

connected by vertical wall portions 10. Each stepped portion 7 includes a horizontal portion 8 and a vertical portion 10, and in the construction shown, there are two stepped portions in the connecting wall 4 between the forward edge of the bottom wall and the upper edge of the rear wall of the cabinet. Secured in each stepped portion of the connecting wall, are receptacle supporting members indicated generally at 11, which are formed of angle members having vertical portions 12, and horizontal portions 13, the vertical portions of the receptacle supporting members 11 being attached in any suitable manner to the horizontal portions 8 of the respective stepped portions of the connecting wall, and the horizontal portions 13 being connected to the corresponding vertical wall 10 of the respective stepped portions. These receptacle supporting members being positioned in the stepped portion 7 of the connecting wall, provide a means for supporting receptacles with the upper free edges thereof in the openings 9, in the horizontal portions 8 of the stepped portion 7. ⁷⁵

The containers or receptacles which are used in connection with this cabinet, are indicated more particularly in Figure 4 of the drawings, and includes suitable receptacles 14 open at the upper end and of a size and shape corresponding to the opening 9 in the horizontal portion 8, and the depths of the receptacles are such that when the bottoms are positioned on the horizontal portions 13 of the receptacle supporting member, the upper open ends will lie flush with the horizontal offset portion 8 of the step portion 7. Each container or receptacle 14 is provided with its individual cover 15, ⁸⁰ hingedly connected thereto and normally adapted to close the upper open end of said receptacle, in a manner as clearly shown in the drawing. ⁸⁵

As illustrated in Figure 3, the receptacle supporting member 11 adjacent the rear wall 2 of the casing is provided with a depending vertical wall portion 16, extending downwardly from the vertical portion 12, to the bottom wall 3 of the cabinet, to provide an additional support for this receptacle supporting member. The bottom wall 3 of the cabinet is provided at the corners thereof with suitable supporting feet 17 for supporting the cabinet in spaced relation above ¹⁰⁰ the floor or other supporting surface. ¹⁰⁵

From the foregoing description, it should

- be clear that the construction provides a jar cabinet of exceedingly simple form, which may, and preferably is, constructed from sheet metal, in order to form a sanitary 5 cabinet construction, for receiving and supporting in a convenient manner, a plurality of similar receptacles, which are adapted to contain fruits and the like at soda fountains or in candy kitchens, in a manner to 10 provide convenient access to all of the receptacles, so that they may be used in the making of sundaes, or candy and the like. For convenience in identifying the contents 15 of these several receptacles in the jar cabinet, vertical wall portions 10 are provided with suitable frames 18, in front of each container for receiving a card containing suitable identification means for the contents of the particular receptacle.
- 20 Having described my invention, what I claim and desire to secure by Letters-Patent, is:—
- 25 A jar cabinet, including a body having a bottom wall, a rear wall, and a connecting wall between the forward edge of the bottom wall and the upper edge of the rear

30 wall, said connecting wall being formed with a plurality of stepped portions having horizontal offset portions and vertical wall portions, said horizontal offset portions being formed with a plurality of openings, and receptacle supporting means of angular form, having vertical portions and horizontal portions, one supporting member being secured in each stepped portion of the connecting wall, and having the vertical portion thereof connected to the horizontal offset portion and the horizontal portion thereof connected to the vertical wall portion for providing a support for a plurality of receptacles inserted through the openings in the horizontal offset portion of the connecting wall, so that the upper end of said receptacle will lie flush with the faces of the horizontal offset portions of the connecting 45 walls, said receptacles being provided with individual covers, and the vertical portion of the rear receptacle supporting member having a depending wall engaging the bottom wall of said cabinet.

50 In testimony whereof I affix my signature.
JAMES BATES.
